UNITED STATES PATENT OFFICE.

HENRY HEITMANN, OF MIAMISBURG, OHIO.

DESIGN FOR A CIGAR.

SPECIFICATION forming part of Design No. 29,089, dated July 26, 1898.

Application filed June 17, 1898. Serial No. 683,758. Term of patent 7 years.

To all whom it may concern:

Be it known that I, HENRY HEITMANN, a citizen of the United States, residing at Miamisburg, in the county of Montgomery and State of Ohio, have invented and produced a new and original Design for Cigars; and I do declare the following to be a clear, full, and exact description of the invention, such as will enable others skilled in the art to which it appertains to make and use the same, reference being had to the accompanying drawings, forming a supplement to the description.

Figure 1 is a vertical elevation of a cigar made in accordance with my design. Fig. 2 is a cross-sectional view of the same.

As is shown in the drawings, the leading or material feature of my design consists in a cigar provided with corrugations and intervening grooves running spirally around the

entire surface of the cigar, so that a unique and distinct appearance is imparted to the cigar.

The spiral corrugations or threads *a* and the intervening spiral grooves *b* extend from near the tip of the cigar in uniform and continuous lines, substantially as shown in the drawings.

Having described my design, I claim as new and desire to secure by Letters Patent—

The design for a cigar as herein shown and described.

In testimony whereof I hereunto affix my signature in the presence of two witnesses.

HENRY HEITMANN.

Witnesses:

A. J. FIORINI,
R. J. McCARTY.
